LLP(57) CLAIM

The ornamental design for a handbag, as shown.

DESCRIPTION

FIG. 1 is a perspective view of a handbag showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

The broken lines on the surface of the claimed design represent unclaimed stitching. The handbag chain is shown with a symbolic break in its length. the appearance of any portion of the article between the break lines forms no part of the claimed design.
